(57) **CLAIM**

The ornamental design for a connector, as shown and described.

DESCRIPTION

FIG. 1 is a top and side perspective view of a first embodiment of a connector embodying our new design;

FIG. 2 is a bottom and side perspective view thereof;

FIG. 3 is a top view thereof;

FIG. 4 is a bottom view thereof;

FIG. 5 is a first side view thereof;

FIG. 6 is a second side view thereof;

FIG. 7 is a front view thereof;

FIG. 8 is a back view thereof; and,

FIG. 9 is another perspective view thereof, shown in an environment of use.

The broken lines in the drawings illustrate environmental features and portions of the connector that form no part of the claimed design.
